UNITED STATES PATENT OFFICE.

JAMES J. FISHER, OF JUNIOR, WEST VIRGINIA, ASSIGNOR OF ONE-HALF TO WILLIAM L. FISHER, OF TUNNELTON, WEST VIRGINIA.

EXPANSIBLE PACKING.

1,386,097.

Specification of Letters Patent.

Patented Aug. 2, 1921.

Application filed November 7, 1919. Serial No. 336,275.

To all whom it may concern:

Be it known that I, JAMES J. FISHER, a citizen of the United States, residing at Junior, in the county of Barbour and State 5 of West Virginia, have invented certain new and useful Improvements in Expansible Packings, of which the following is a specification.

This invention relates to improvements in 10 expansible packings for the water pump of a steam engine though not necessarily restricted to such use.

An important object of this invention is to 15 provide a packing for pumps and the like having novel means whereby the packing may be periodically adjusted for taking up the wear on the same.

A further object of this invention is to 20 provide an expansible packing which when arranged within a cylinder may be conveniently and expeditiously adjusted from one end of the head to which it is applied whereby access may be had to the adjusting means by removing the cylinder head.

25 A further object of the invention is to provide an expansible packing having means whereby the entire contact surface of the packing may be engaged with the inner wall of the cylinder with a uniform degree of 30 pressure.

A further object of this invention is to 35 provide an expansible packing which is efficient, of highly simplified construction and durable in use.

Other objects and advantages of the 40 invention will be apparent during the course of the following description.

Figure 1 is a perspective of the improved 45 expansible packing applied;

Fig. 2 is a transverse section through a follower head having the improved packing applied, the packing being shown contracted;

Fig. 3 is a similar view, the packing being 50 shown expanded;

Fig. 4 is a vertical section through a follower head having the expansible packing;

Fig. 5 is a perspective of the several elements of the invention detached.

55 In the drawings wherein for the purpose of illustration is shown a preferred embodiment of the invention, the numeral 10 designates a cylinder in which is arranged a reciprocating piston rod 11. A follower head 12 is formed integral with the rod 11 and is

provided with an annular flange 13 at one end. The annular flange 13 co-operates with a face plate 14 which extends beyond the side of the head at the opposite end of the same for securing a plurality of packing 60 rings 15 about the follower. As illustrated in Fig. 1 the packing rings 15 are split and have their end portions provided with reduced interlocking tongues or extensions 16 which are slidable with relation to each 65 other. The packing rings tightly engage the inner wall of the cylinder and provide a liquid tight engagement between the head 12 and the cylinder.

To provide means for adjusting the packing rings 15 to compensate for the wear on the same a plurality of arcuate sections 17 are arranged about the head 12 and have their adjacent ends connected by contractile coil springs 18. The end portions of the 75 coil springs 18 extend into openings 19 in the ends of the sections 17 and are provided with attaching loops 20 which receive locking pins 21. The locking pins 21 are mounted within recesses 22 in the outer sides of 80 the sections 17 which communicate with the openings 19 in the ends of the sections.

A plurality of spaced slots or grooves 23 are provided in the outer side of the head 12 and extend longitudinally of the same. The 85 grooves 23 extend out through the ends of the head 12 and into the flange 13 as indicated at 24. The arcuate sections 17 are provided with grooves 25 opening out through the opposite ends of the same and 90 arranged in opposed relation to the grooves 23. As best illustrated in Fig. 4, the opposed walls of the grooves 23 and 25 converge toward the face plate 14 and receive

wedges 26 having inclined sides corresponding to the inclination of the opposed bottom walls of the slots 23 and 25 whereby the forward longitudinal movement of the wedges forces the sections 17 outwardly. Adjusting bolts 27 have threaded engagement with 100 the wedges 26 and pass through openings 28 in the plate 14. The outer end portions of the bolts 27 are provided with integral heads 29 adapted to be rotated for adjusting the wedges as desired. Locking arms 30 are 105 pivoted at their outer ends as indicated at 31 to the outer side of the plate 14 and are provided with slots 32 opening out through one of their sides and adapted to engage the squared portions 33 of the adjusting bolts 110

27 for locking the same against accidental rotation. The constant tendency of the wedges 26 to draw the bolts 27 inwardly causes the heads 29 to tightly engage the locking arms to secure the same in position.

5 A split metallic collar 34 is arranged between the packing rings 15 and the head 12 and has its end portions 35 overlapped as indicated in Fig. 3 to permit the collar to be 10 readily expanded for uniformly expanding the rings 15.

15 A threaded extension 36 is provided on the outer end of the head 12 and extends through a centrally arranged opening 37 in the plate 14 and is engaged by a nut 38. A washer 39 of any desired type is arranged on the threaded extension 36 inwardly of the nut 38.

20 In assembling the improved expandable packing the wedges 26 are first arranged in the grooves 23 and the arcuate sections 17 are subsequently arranged about the head 12 whereby the inclined sides of the wedges 26 may be received within the slots 25. The 25 split collar 34 is now arranged about the segmental sections for forming a relatively smooth seat for the packing. After the packing is applied the face plate 14 is arranged on the outer side of the head 12 and is secured in position by the nut 38. In adjusting the packing, the wedges 26 are all drawn up equal distances for forcing the arcuate sections 17 outwardly. The uniform outward movement of the arcuate sections 17 35 expands the split collar 34 and thereby presses the packing rings 15 into liquid-tight engagement with the inner wall of the cylinder. The coil springs 18 serve to retain the arcuate sections securely in engagement with the wedges 26 and eliminate any tendency of the sections 17 to partake of lateral movement with respect to the head 12 when the sections 17 are in their expanded 40 positions.

45 In adjusting the packing rings when required the cylinder head may be removed to afford direct access to the heads 29. Upon moving the locking arms out of engagement with the squared portions of the bolts 27, the wedges 26 may be drawn into the narrower portions of the slots 23 and 25 whereby the arcuate sections 17 are moved outwardly the desired distance.

55 With reference to the foregoing description and the accompanying drawings it will be apparent that I have provided an expandable packing which may be expeditiously adjusted entirely from one end of the cylinder and the necessity for dismantling the 60 cylinder to any great extent to afford access to the adjusting means is thereby eliminated.

65 It is to be understood that the form of the invention herewith shown and described is to be taken as preferred example and that

such minor changes in arrangement and construction of parts may be made as will remain within the spirit of the invention and the scope of what is claimed.

Having thus described the invention, what 70 is claimed as new is:

1. In an expandible packing, a plurality of arcuate sections having their adjacent ends yieldably connected, a packing surrounding the arcuate sections, and means to 75 adjust the arcuate sections.

2. In an expandible packing, a plurality of arcuate sections having their adjacent ends yieldably connected, a collar surrounding the arcuate sections, a packing surrounding said collar, and means to adjust said arcuate sections. 80

3. In an expandible packing, a plurality of sections, spring means to normally retain said sections contracted, a split collar surrounding said sections and having its adjacent end portions overlapped, expandible packing surrounding said collar, and means to adjust said sections. 85

4. In an expandible packing, a plurality of sections having rounded outer faces, spring means urging the sections inwardly, packings surrounding said sections, and means whereby said sections may be adjusted. 95

5. The combination with a head, of a plurality of sections surrounding the head, a packing surrounding said sections, said sections and said head having longitudinally extending grooves, wedges arranged in said 100 grooves, the inner walls of said grooves and the adjacent walls of said wedges being inclined, adjusting devices connected to said wedges and extending exteriorly of the outer side of the head whereby the wedges may be 105 adjusted from the outer side of the head, and means yieldably connecting said sections.

6. The combination with a head, of a plurality of sections surrounding the head, a packing surrounding said sections, spring 110 means connecting the adjacent ends of said sections for normally retaining the same contracted, said sections and said head being provided with opposed grooves, wedges arranged in said grooves, the inner walls of 115 said grooves and the adjacent sides of said wedges being inclined, a face plate carried by the head, adjusting devices connected to said wedges and extending through said face plate, and means carried by said face plate 120 for locking said wedges in adjusted positions.

7. The combination with a head having an annular flange at its inner end, of a face plate arranged on the outer end of the head 125 and extending beyond the side of the same, a plurality of sections surrounding the head, means yieldably connecting the sections, a split collar surrounding the sections and having its end portions overlapped, an expansi- 130

ble packing arranged about said collar and confined between said annular flange and said face plate, adjusting devices arranged between said sections and said head and extending exteriorly of said face plate, and means arranged on the outer side of the face plate for locking said adjusting devices.

8. The combination with a cylindrical head, of sections surrounding the cylindri-

cal head and having openings in the adjacent sides, springs having their end portions anchored within said openings and adapted for normally retaining said sections contracted, expansible packing arranged about the sections, and adjusting devices engaging the sections.

In testimony whereof I affix my signature.
JAMES J. FISHER. [L. s.]
